[57] CLAIM

The ornamental design for a socket for knockoff wheel hubs, as shown and described.

DESCRIPTION

FIG. 1 is a perspective view in reduced scale of a socket for knockoff wheel hubs showing my new design;

FIG. 2 is a top plan view thereof;

FIG. 3 is a bottom plan view thereof;

FIG. 4 is a side elevational view thereof, the opposite side being a mirror image;

FIG. 5 is a front elevational view thereof, the rear elevational view being a mirror image;

FIG. 6 is a top plan view of the second embodiment thereof;

FIG. 7 is a front elevational view of the embodiment of FIG. 6;

FIG. 8 is a side elevational view of the embodiment of FIG. 6, the opposite side being a mirror image thereof; and,

FIG. 9 is a rear elevational view of the embodiment of FIG. 6.

The bottom plan view of the second embodiment is identical to the bottom plan view of the first embodiment shown in FIG. 3.

FIG. 2

FIG. 4

FIG. 3

FIG. 5

FIG. 6

FIG. 7

FIG. 8

FIG. 9
